UNITED STATES PATENT OFFICE.

WALTER G. KING, OF NEW YORK, N. Y.

DESIGN FOR A NOSE-GUARD.

43,049.

Specification for Design.

Patented Sept. 24, 1912.

Application filed March 22, 1912. Serial No. 685,590. Term of patent 14 years.

To all whom it may concern:

Be it known that I, WALTER G. KING, a citizen of the United States, residing at New York, in Queens county and State of New York, have invented a new, original, and ornamental Design for Nose-Guards, of which the following is a specification, reference being made to the accompanying drawings, forming a part thereof.

Figure I represents a plan view of my

improved design for nose guards, and Fig. II represents an edge view thereof.

I claim:

The ornamental design for a nose guard as shown.

WALTER G. KING.

Witnesses:

LEO WORMSER,
B. W. KING.
